Patented July 26, 1921.

FIG. 1

FIG. 2

FIG. 3

FIG. 5

FIG. 4

James U. Duffy.
By May, Oberlin & Day, ATTYS.

UNITED STATES PATENT OFFICE.

JAMES U. DUFFY, OF CLEVELAND, OHIO, ASSIGNOR TO THE FRICTION CAR STOP COMPANY, OF CLEVELAND, OHIO, A CORPORATION OF OHIO.

CAR-STOP SHOE.

1,385,528.

Specification of Letters Patent. Patented July 26, 1921.

Application filed December 5, 1919. Serial No. 342,813.

To all whom it may concern:

Be it known that I, JAMES U. DUFFY, a citizen of the United States, and a resident of Cleveland, county of Cuyahoga, and State of Ohio, have invented a new and useful Improvement in Car-Stop Shoes, of which the following is a specification, the principle of the invention being herein explained and the best mode in which I have contemplated applying that principle, so as to distinguish it from other inventions.

The present invention relates to shoes such as are adapted to be used in car stops of the type shown in U. S. Letters Patent No. 1,276,273 dated August 20, 1919, granted to Edward Breyley and myself and in my co-pending application Serial No. 329,724, filed October 10th, 1919.

These shoes are adapted to receive the wheel or wheels of a railway car or the like and are then adapted to slide along under the wheel until the friction between the shoe and the rail brings the shoe, and thus the car, to a stop. The shoes are constructed so as to receive either one or both wheels of a car truck and are so designed that the wheel is lifted away from the rail and carried in the shoe itself. The shoes are so formed that when the car is moved backwardly the shoe is returned with the car until the shoe is prevented from moving farther by any suitable type of stop placed either on or adjacent the rail. It is, of course, understood that the shoes are generally used in pairs, there being one on each rail, and these shoes will be mounted on the rails so as to receive the wheels of the truck at the same time. To the accomplishment of the foregoing and related ends, said invention, then, consists of the means herein-after fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

Figure 1 is a side elevational view of a rail and shoe embodying my invention: Fig. 2 is a similar view of a slightly modified form of shoe: Fig. 3 is a similar view of another form of shoe showing the normal position of the wheels in dotted lines: Fig.

4 is a section taken on the line 4-4 of Fig. 3: and Fig. 5 is a section taken on the line 5-5 of Fig. 3.

In the form shown in Fig. 1 there is a rail 1 upon which is mounted a shoe 2 which is provided with legs 3 and 11 passing down over the ball of the rail, which maintain the shoe in position thereon. At one end 4 of the rail there is mounted a bumper 5 of the usual type and at the other end of the rail is shown a permanent stop 6 which is adapted to limit the forward or return movement of the shoe.

The shoe itself is preferably a casting provided with the legs as before stated, and having an inclined forward surface or portion 7 which ends in a curved receiving portion 8 in which the car wheel is adapted to fit and be held off the rail. The rear portion 9 of the shoe is high enough to prevent the wheel from jumping out of the curved portion and rolling beyond the shoe. The inclined forward surface 7 is high enough so that the curved portion 8 which receives the wheel lies below the upper plane 75 of the inclined portion, thus forming a hump 10 which prevents the wheel from rolling out of the shoe upon rear movement of the car until the forward leg 11 of the shoe contacts the block mounted on the rail and thus 80 prevents further movement of the shoe.

In Fig. 2 I have shown a slightly modified form of shoe 12 which is provided with legs 13 as in the first form, and which is mounted on the rail 14 provided with permanent 90 stops 15 and 16 ahead of and behind the shoe to limit the movement of the shoe in both directions. This shoe is provided with a rear portion 17 of approximately the same height as the rear portion of the first form 95 of the shoe, and it also has a forwardly inclined portion 18 which tapers off to the rail, but this inclined portion 18 is spaced away from the rear portion a sufficient distance to allow both wheels of the truck to 100 ride upon the shoe. The forward wheel 19 of the truck seats in the curve 20 of the rear portion and the rear wheel of the truck seats in the curve 21 adjacent the top 105 of the inclined forward portion of the shoe.

This shoe operates exactly as the shoe in the first form mentioned, except that both wheels are carried by the shoe and the hump 10 is adapted to prevent the wheels from 110 being removed from the shoe or rolling off

the same until the forward leg of the shoe contacts the stop 15 mounted on the rail.

- The remaining figures show another form of shoe having the usual legs 25 which extend downwardly and embrace the ball of the rail, the shoe being provided with the rear portion 26 having the curved seat 27 for the wheel and being also provided with the inclined front portion 28 and hump 10, 10 which has a curved surface 29 toward the rear portion, as in the other forms. In this form the distance between the curved seat 27 in the rear portion and the hump is slightly greater than in the form shown in 15 Fig. 1, thus allowing the forward wheel 30 of the truck to have some rolling movement between the rear portion and the hump. The shoe is long enough, however, to allow the rear wheel 31 of the truck to ride upon 20 the inclined forward portion 28 when the shoe is acting to stop the car, the wheels when this is being done, being indicated by dotted lines in Fig. 3. When the car is pulled rearwardly, the rear wheel 31 of the 25 truck rolls off the shoe, while the forward wheel 30 rides up against the hump 10 and pulls the shoe along with the car and wheel until the legs 25 of the shoe contact the fish plates 32 between the rail ends. 30 In Fig. 4 the section is taken through the rail 2 where the fish plates 32 are mounted. This section shows the forward legs 25 of the shoe as contacting the ends of these plates 32 to prevent further movement of 35 the shoe, thus allowing the wheels to be withdrawn from the shoe. Fig. 5 shows the form of the legs of the shoe which embrace the ball of the rail and thus hold the shoe in place thereon. 40 In the present form of shoe the hump, combined with the curved portion of the shoe adjacent the same serves to act as a return of the shoe, this hump being so proportioned that the shoe will return with 45 the car wheel until it engages the stop or fish plate on the rail, at which time the shoe will be prevented from further movement and the wheel will ride over the hump and thus off the shoe. In the first two forms I 50 have shown permanent stops mounted on the rail, the stop in Fig. 1 being indicative of the usual bumper and showing in dotted outline the car frame 35 against such bumper. In Fig. 2 I have shown a permanent stop mounted on the rail, this stop being similar to those indicated in my co-pending application hereinbefore mentioned. In the form shown in Fig. 3 no permanent stop has been indicated, it being 55 understood that the shoe will bring the car to a stop within a reasonable distance, this distance depending merely upon the velocity and weight of the car at the time it engages the shoe. In this form I have also 60 shown the shoe as contacting the fish plates 65

of a rail to prevent or limit the return movement of the shoe.

The present shoes are adapted to be used in pairs, the first form of shoe being suitable for use in stopping single cars, or in light work, while the other two forms are more adapted to heavy use where several cars are coupled together, or where the cars have very heavy loads. The shoes all act in the same way, being self-contained and being adapted to move in both directions with the car wheel, so that when the car is withdrawn, the shoe is left in position to receive the next car that is to be stopped. The shoes are easy to make and may be slid onto a rail and operated without constant attention. The forward stop or fish plate acts as a positioning means so that the shoes will always be in position to receive and stop a car.

85 Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. A shoe for car stops, comprising a member adapted to be slidably mounted on a rail with stops, said member comprising a curved, wheel receiving portion and an inclined forward portion, the forward portion forming a hump adapted to hold said wheel 100 in said shoe during return movement of said wheel toward the stop.

2. A shoe for car stops, comprising a member adapted to be slidably mounted on a rail with stops, said member comprising a curved, wheel receiving portion and an inclined forward portion, the bottom of said curved portion lying below the upper end of said inclined portion and forming a hump 110 adapted to hold said wheel in said shoe whereby said shoe will move back with said wheel along the rail to the stop.

3. A shoe for car stops comprising a member adapted to be slidably mounted on a rail and having legs adapted to embrace the rail, said member having a raised rear portion provided with a curved wheel receiving portion and an inclined forward portion adapted to allow the wheel to roll up the same into said receiving portion, the lower part of said receiving portion being below the top of the inclined portion, forming a hump adapted to engage with the car wheel upon return movement of the car.

4. A shoe for car stops comprising a member adapted to be slidably mounted on a rail and having legs adapted to embrace the rail, said member having a raised rear portion provided with a curved wheel receiving portion, and an inclined forward portion

- adapted to allow the wheel to roll up the same into said receiving portion, said inclined portion forming a hump and being spaced away from said wheel receiving portion a sufficient distance to allow both car wheels to ride on said shoe during forward movement of the same.
5. A shoe for car stops comprising a member adapted to be slidably mounted on 10 a rail and having legs adapted to embrace the rail, said member having a raised rear portion provided with a curved wheel receiving portion, and an inclined forward portion adapted to allow the wheel to roll 15 up the same into said receiving portion, said inclined portion forming a hump and being spaced away from said wheel receiving portion a sufficient distance to allow both car wheels to ride on said shoe during forward
- movement of the same, said hump being 20 adapted to engage the car wheel upon return movement to return said stop therewith.
6. A shoe for car stops comprising a member adapted to be mounted on a rail and 25 having a curved wheel receiving portion and inclined portion, the inclined portion ending above the wheel receiving portion forming a hump adapted to engage with the car wheel to move said shoe with said wheel 30 upon return movement of the latter and cooperating means on said shoe and rail as adapted to limit return movement of said shoe and hold the same to allow the wheel 35 to ride over said hump and off said shoe.

Signed by me, this 3rd day of December, 1919.

JAMES U. DUFFY.
